AIR COMPRESSOR

Laurence D. Harrison, Phoenix, Ariz.

Application June 30, 1937, Serial No. 151,167

6 Claims. (Cl. 230—222)

My invention relates to air compressors of the reciprocating type wherein air is drawn into a cylinder through an intake valve and discharged through an exhaust valve into a receiving chamber, and its objects are: First, to provide a compressor of the type mentioned wherein both intake and exhaust valves are mechanically operated in order to secure the proper uniform action thereof, regardless of working pressures; second, to provide a compressor of the type disclosed wherein the valves are mechanically operated so that the pistons may operate at speeds comparatively much higher than the conventional type heretofore used; third, to provide a compressor of the type disclosed wherein mechanical means is provided to prevent or stop the action of said compressor when desired; fourth, to provide a compressor of the type described wherein leaks around the mechanically operated exhaust valve are prevented; fifth, to provide a device of the kind disclosed wherein strain on the exhaust valve due to the pressure built up in the receiver tank is equalized whereby the exhaust valve is not placed on a strain such as to cause its fracture when operated at high speeds; and, sixth, to provide mechanism associated with a compressor of the type described wherein the exhaust valve opens only after a predetermined pressure has been built up in the working cylinder. Other objects will appear hereinafter.

I attain these objects by means of the particular design and construction of the compressor illustrated in the accompanying drawing herewith made a part of this application in which—Fig. 1 is a vertical mid-section of the upper portion of a compressor head embodying my improvements, taken on a plane parallel with the axis of the crank shaft; Fig. 2 is a plan view of the cylinder head, as shown in Fig. 1, with the cam lifting mechanism shown in section; Fig. 3 is a vertical section taken substantially on line 3—3, Fig. 2; Fig. 4 is a vertical section taken substantially on line 4—4, Fig. 2; Fig. 5 is a diagrammatic elevation of a cylinder showing the crank and cam mechanism; and Fig. 6 is a modified form, in section, of an exhaust valve accordion spring.

Similar numerals refer to similar parts in all views.

Heretofore the practice has been to construct air compressors with both valves operating automatically from the pressures created by differential air pressures created by the movement of the piston within the cylinder. These valves were variously termed, but are commonly known as weak-spring or flutter valves. The intake

valve was positioned so that when a slight vacuum was created it would open, permitting air to enter the cylinder and would close whenever pressure was created by the opposite stroke of the piston within the cylinder. Conversely, the exhaust valve was constructed so that it would open against the pressure of its closing spring whenever pressure was created within the cylinder greater than that in the receiving tank, and would close under this pressure and by reason of its spring upon the down or outer stroke of the piston. When pressure had been sufficiently built up within the receiver, action of the compressor was stopped, by holding open the intake valve by mechanical lever arrangement. This practice necessitated the use of heavy, large and slow moving parts in order to furnish compressed air in volumes desired for commercial purposes, since it is impossible to operate these automatic valves beyond a certain speed due to their inertia, etc.

This was particularly true of the exhaust valve. If, on the other hand, this valve was made lighter to minimize the inertia, it was found in practice that it soon hammered itself out of its seat or became entirely broken or crystallized and subject to breakage. This same condition was true of the intake valve to a lesser degree. Due to this drawback, therefore, it was necessary for air compressors to have a large piston displacement and operate at comparatively slow speeds, hardly ever exceeding 900 R. P. M.

In order to provide mechanism which would furnish an equal volume of air compressed to the required pressure, I have provided the mechanism hereinafter described, and illustrated in the accompanying drawing, in which the valves are caused to operate mechanically and, therefore, can be made much heavier and larger in order to stand the strain to which they are subject and since these valves do not depend upon differences of air pressure to cause them to operate, they may be timed to open and close at the desired positions of the piston and to open sufficiently to provide a free unobstructed passage for the air being pumped.

As illustrated in the accompanying drawing, 2 designates the top end of the cylinder, 3 the cylinder head, 4 the intake valve and 5 the exhaust valve.

These valves are seated in the usual manner in the cylinder head provided with an intake port 23 leading from the outer air, and exhaust port 24 connected to a compressed air receiver.

With reference to the intake valve, it will be

noted that it is held shut under the tension of spring 6 in the usual manner, and is mechanically operated by the rocker arm 7, operatively mounted on an eccentrically positioned journal 8 on rocker arm shaft 9. This rocker arm is in turn operated by push rod 10 from cam 25, operating at the same speed as crank shaft 35 and indicated diagrammatically in Fig. 5.

Exhaust valve 5 is fitted within the head 3 the same as the intake valve, which is opposite to the conventional manner in which exhaust valves of air compressors are positioned. It is held shut under the tension of the spring steel accordion bellows 12, which is attached to the upper part 15 of the valve stem by an air-tight seal 13 and to the cylinder head 3 by a similarly air-tight seal 14, held in place by a large bushing 15. This exhaust valve is operated by a rocker arm 16, operatively supported on an eccentrically positioned journal 17 on shaft 9, and operated by push rod 22 from cam 26 revolving at crank shaft speed.

Shaft 9 is rotatably supported and journaled to turn in support brackets 18, attached to cylinder head 3. It is provided at one end with a bell 25 crank 19, which may be operated by any convenient leverage means to swing through an arc of approximately 90°. It is to be noted that the center of the journal 8 on which the rocker arm 7 is mounted is oppositely positioned to that of the journal 17, on which rocker arm 16 is mounted. When the shaft 9 is in the neutral position, as illustrated in Figs. 3 and 4, both valve tappets are operative. If, however, it is swung 30 90° in the direction of the arrow, it will be noted that the journal axis of rocker arm 7 is lowered. This has the effect of holding open the intake valve. On the other hand, eccentric 17, supporting the exhaust valve rocker arm, is raised so that the rocker arm does not operate the valve which, 35 therefore, remains closed. By rotating this rocker arm shaft the operation of these valves may be regulated and the device caused to idle, although the shaft and piston may continue to rotate. Air will be pumped in and out of the 40 intake manifold but air pressure will be maintained in the receiver by reason of the inoperation of the closed exhaust valve. This construction also avoids the possibility of the compressor stopping at a point with the exhaust valve open, which 45 would cause a loss of pressure from the receiver or damage to the driving machinery by reason of a back motion of the piston. Rocker arm springs 27 and 28 are connected between the cylinder head and the rocker arms 7 and 16 respectively, to cause these arms to remain in operative position on, or ride, the upper ends of the push rods, regardless of the position of the 50 rocker arm shaft or its movements.

The accordion spring 12 is made with sufficient tension to hold the exhaust valve 5 closed, against any predetermined pressure in the receiver. Air pressure from exhaust port 24 enters the closed chamber 20, through vent opening 29 and, pressing outwardly, tends to offset the pressure exerted 55 against the valve disk 21, which tends to open it. Therefore, higher pressure than that which the spring would otherwise be capable of holding by itself, may be maintained in the receiver. The action of the accordion valve spring, therefore is 60 three-fold—First, it prevents pressure from leaking from the receiver out through the valve stem; second, it operates as an offset chamber to equalize the pressure on the valve disk and assist in maintaining it closed; and, third, it acts as a 65 valve spring. In the alternative form shown in 70

Fig. 6, the accordion 30 may be made of softer metal while the assistant spring 31 is used to furnish the tension and keep the valve closed.

Push rod 22, operating rocker arm 16, cooperates with cam 26 in the usual manner. Its lift, however, is positioned so that exhaust valve 5 is not opened until the upwardly traveling piston 32 has approached the upper end of its stroke as shown in Fig. 5 and has compressed the air in the cylinder to a predetermined pressure approximately equal to that to be maintained in the receiver. Thus, after a charge is drawn in and compression started, the only pressure against the upwardly traveling piston is that of the compression of the charge just received, until it 10 slightly exceeds the working pressure and the valve opens. Therefore, the piston does not have to work against the full pressure of the receiver tank throughout the whole upper stroke.

Operation is as follows: Air is drawn from intake port 23 through the intake valve, operated by a cam timed to lift so that it fully opens soon after the commencement of the intake stroke and stays open until the piston has practically reached the bottom of its travel. On the up 25 stroke the intake valve closes and the exhaust valve remains closed until the piston reaches a point, as above stated, where the pressure in the cylinder approximates that to be maintained in the receiver. At this point the exhaust valve 30 opens and remains open until the piston reaches the upper limit of its travel, when it again closes. Now, if sufficient pressure has been built up in the receiver, and it is desired to momentarily stop compressing, rocker arm shaft 9 is rotated 35 throughout approximately 90° in the direction of the arrows in Figs. 3 and 4. This shifts the position of both of the eccentric portions of the rocker arm shaft 9, as above explained, and causes the axis of rocker arm 7 to be lowered so 40 that it remains open even though its push rod operates. On the other hand, the axis of rocker arm 16 is raised so that it does not contact the top of the stem of valve 5, although it continues to ride in operative position on its push rod by 45 reason of the tension of spring 28. This simple and effective means permits the regulation of the pressure in the receiver, and bell crank 19 may be operated through any convenient lever system either manually or by a pressure regulating 50 accordion diaphragm connected with the receiver tank.

Since both valves operate mechanically at a predetermined timed position, and the tension of their springs may be sufficient to make a closure at 55 all times, it is obvious that this type of mechanism is not hampered by inertia which limits the speed of automatically operated valves. For this reason, an air compressor provided with my valve mechanism may be made of much smaller size, 60 and by increasing its crank shaft speed, will easily deliver the same volume of air at the same pressure as the heavier and more bulky compressors now in general use. While compressors ordinarily do not operate at a speed greater than 65 900 R. P. M., compressors of the type here disclosed may be operated at speeds as high as 3,500 R. P. M., thus permitting a great saving in space and weight, as well as making it more economical in maintaining valves in good condition.

I wish to be limited only by the following claims.

I claim:

1. Valve mechanism for air compressors of the reciprocating piston type comprising in combina- 75

tion a cylinder head being ported and provided with valve seats for an intake and exhaust valve to open inwardly into said cylinder chamber, intake and exhaust valves seated therein having 5 their stems protruding outward from said cylinder head, a helical spring intermediate said cylinder head and the outer end of said intake valve, an accordion spring intermediate said cylinder head and the outer end of the stem of said exhaust 10 valve, means for sealing said accordion spring to the cylinder head and the place of its attachment on the stem of said exhaust valve respectively, rocker arms adapted to operatively open said valves supported on the rocker arm shaft attached to said cylinder head with the journal 15 supporting said intake valve eccentrically positioned relative to the axis of said rocker arm shaft and the journal supporting said exhaust valve rocker arm eccentrically positioned relative to the 20 axis of said rocker arm shaft, the axes of said eccentrically positioned journals being oppositely positioned relative to the axis of said rocker arm shaft, push rod mechanism for alternately operating said valve, and means for axially rotating 25 said rocker arm shaft throughout a predetermined arc.

2. Valve mechanism for reciprocating air compressors comprising a cylinder head provided with an intake port and exhaust port and valve 30 seats communicating therewith to receive inwardly opening poppet valves, an intake valve operative in said intake port valve seat having its stem protruding outwardly through said cylinder head and a spring normally holding said valve 35 shut intermediate said cylinder head and the outer end of said valve stem, an exhaust valve seated in said exhaust valve port seat having an outwardly extending stem, a spring consisting of a resilient accordion cylinder annularly surrounding said exhaust valve stem and provided with an air-tight seal at its outer end to the outer end of the valve stem of said exhaust valve and a seal at its lower end forming an air-tight closure to 40 said cylinder head, together with mechanism for mechanically operating said valves at predetermined intervals.

3. Valve mechanism for reciprocating air compressors comprising a cylinder head provided with an intake port and exhaust port and valve seats 50 communicating therewith to receive inwardly opening poppet valves, an intake valve operative in said intake port valve seat having its stem protruding outwardly through said cylinder head and a spring normally holding said valve shut intermediate said cylinder head and the outer end of said valve stem, an exhaust valve seated in said exhaust valve port seat having an outwardly extending stem, a spring consisting of a resilient accordion cylinder annularly surrounding said 55 exhaust valve stem and provided with an air-tight seal at its outer end to the outer end of the valve stem of said exhaust valve and a seal at its lower end forming an air-tight closure to said cylinder head, together with mechanism for alternately operating said valves at predetermined intervals comprising rocker arms, push rods and cam 60 operatively associated with the crank shaft of said compressor, said rocker arms being supported on a rotative rocker arm shaft and having bearings operative on journals eccentrically positioned relative to the axis of said rocker arm shaft, the centers of said eccentric journals being disposed at uniform distances on either side of the axis of said rocker arm shaft, and means for 65 rotating said rocker arm shaft a predetermined

distance whereby to shift the axes of said eccentrically positioned rocker arm journals.

4. Valve mechanism for reciprocating air compressors comprising a cylinder head provided with an intake port and exhaust port and valve 5 seats communicating therewith to receive inwardly opening poppet valves, an intake valve operative in said intake port valve seat having its stem protruding outwardly through said cylinder head and a spring normally holding said valve 10 shut intermediate said cylinder head and the outer end of said valve stem, an exhaust valve seated in said exhaust valve port seat having an outwardly extending stem, a spring consisting of a resilient accordion cylinder annularly surrounding said exhaust valve stem and provided with an air tight seal at its outer end to the outer end of the valve stem of said exhaust valve and a seal at its lower end forming an air-tight closure 15 to said cylinder head, together with mechanism 20 for alternately operating said valves at predetermined intervals comprising rocker arms, push rods and cams operatively associated with the crank shaft of said compressor, said rocker arms being supported on a rotative rocker arm shaft 25 and having bearings operative on journals eccentrically positioned relative to the axis of said rocker arm shaft, the centers of said eccentric journals being disposed at uniform distances on either side of the axis of said rocker arm shaft, 30 and means for rotating said rocker arm shaft a predetermined distance whereby to shift the axes of said eccentrically positioned rocker arm journals.

5. In a reciprocating air compressor, valves and 35 associated mechanism comprising inwardly opening poppet intake and exhaust valves communicating with the compressor cylinder, positive means for opening said valves at pre-determined intervals, including rocker arms, push rods and cams operative from the compressor crank shaft, a combined valve closing spring and sealing means 40 surrounding the exhaust valve stem adapted to prevent leakage from the compressed air receiver back through the valve stem chamber, and passageways communicating air pressure from said receiver to said sealing means whereby back pressure from said receiver pushing outward tends to hold said inwardly opening exhaust valve 45 closed.

6. In a reciprocating air compressor, valves and 50 associated mechanism comprising inwardly opening poppet intake and exhaust valves communicating with the compressor cylinder, positive means for opening said valves at pre-determined intervals, including rocker arms, push rods and cams operative from the compressor crank shaft, a combined valve closing spring and sealing means 55 surrounding the exhaust valve stem adapted to prevent leakage from the compressed air receiver back through the valve stem chamber, and passageways communicating air pressure from said receiver to said sealing means whereby back pressure from said receiver pushing outward tends to hold said inwardly opening exhaust valve closed, together with means 60 for rendering said valves inoperative by holding said intake valve open and permitting said exhaust valve to remain closed, comprising a rotatable rocker arm shaft having eccentrically positioned 65 rocker arm journals thereon with their eccentric centers substantially oppositely positioned relative to the axis of said rocker arm shaft.
